UNITED STATES PATENT OFFICE.

HARRY E. LA BOUR, OF CHICAGO, ILLINOIS.

PUMPING SYSTEM.

Application filed May 2, 1921. Serial No. 466,195.

To all whom it may concern:

Be it known that I, HARRY E. LA BOUR, a citizen of the United States, residing at Chicago, in the county of Cook and State of Illinois, have invented a certain new and useful Improvement in Pumping Systems, of which the following is a full, clear, concise, and exact description, reference being had to the accompanying drawings, forming a part of this specification.

My invention relates to pumping systems, and more specifically to an improvement in the self-priming type of pumping system. One object of my invention is to provide such a system having a valveless pump capable of handling a mixture of gas and liquid.

Another object is to provide for continuous automatic and complete removal of any gas in the suction line of such a system.

Another object is to improve the automatic control of the priming action.

Further objects and advantages of my invention will become apparent as the description proceeds.

In the accompanying drawings:

Figure 1 is an elevation of the main parts of a pumping system constructed according to my invention;

Figure 2 is a detail section of the portion of the piping in which the mixture of gas and liquid occurs;

Figure 3 is an elevation similar to Figure 1 of a manually operated system;

Figures 4 and 5 are sections in vertical planes at right angles of the improved pump employed in my system; and

Figures 6 to 11 are diagrammatic views indicating different ways for raising liquid by suction with a valveless pump.

In the embodiment of my invention illustrated in Figure 1, the suction pipe 10 is adapted to draw liquid, as for instance water, from any suitable source to the system shown and the discharge pipe 12 conveys the liquid under pressure generated by the pump to any desirable distribution system. The discharge pipe 16 receiving the liquid impelled by the pump 14 opens into a separator 18 at a point spaced somewhat above the bottom thereof as at 20, and the discharge pipe 12 is connected directly to the upper end of the separator. A horizontal pipe 22 communicates with the separator 18 adjacent the bottom thereof, said horizontal pipe being equipped with a shut-off valve 24

if desired. From pipe 22, a vertical pipe 26 leads to a mixing head 28 into which the inlet pipe 10 also opens. From the lower side of the head, a pipe 30 connects with the horizontal pipe 32 opening into the pump 14. In the pipe 12, I mount a pressure relief valve 33 adjusted to open at a pressure materially lower than that which the system is designed to develop.

The main features of operation of a system according to my invention will be more clearly understood after a consideration of the diagrams of development indicated in Figures 6 to 11 of the drawings.

The primary difficulty involved in using a valveless pump to draw liquid by suction, is that whenever the pump is stopped, the suction line will fill with air or other gas. The first and most obvious answer to such an objection is to make a pump capable of handling either liquid or gas. Such a system is indicated in Figure 6, and as far as the system is concerned, would appear to be simplest and most desirable. Unfortunately, the differences in the physical properties of the two mediums to be handled by the pump are so great that no valveless pump has yet been designed capable of handling liquid with reasonable efficiency, and at the same time, capable of handling gas so as to develop any effective vacuum.

Having been forced to the conclusion that the pumping system indicated in Figure 6 cannot be realized because no such pump as that required is available; we next proceed to inquire what can be accomplished with such a pump as that disclosed in my copending application hereinafter referred to, which pump is capable of handling a mixture or emulsion of liquid and gas with fair efficiency, and is at the same time, very efficient in handling liquid unmixed with gas.

The problem therefore resolves itself into producing a suitable mixing means for mixing enough liquid with the gas in the suction line, so that the mixed mass can be ejected by the pump. Liquid being available in the reservoir 68, it would be possible to generate a flow of air through the rest of the system, and by gradually lowering a movable extension 70 forming part of the suction line to aspirate liquid from reservoir 68 as indicated by the arrows at 72 into the air in the suction line. Figure 8 indicates the final position of the extension 70 which could be attained by very

gradual movement downward from the position indicated in Figure 7. At this time, the gas in the suction line has been completely eliminated and pump 74 is handling 5 masses of liquid practically unmixed with gas. There are, however, many practical objections to such a method of mixing; some of the more important ones being that the joints between extension 70 and the 10 suction line 76 would be apt to leak, and that the surface of the liquid in the reservoir is in many instances not steady enough to permit of the successful operation of such a device.

15 To obtain an efficient mixing action for assisting pump 74 in evacuating the suction line 76, we might employ an auxiliary pump, such as that indicated diagrammatically at 78, the pump illustrated being 20 a valved piston pump drawing liquid direct from the reservoir 68 and delivering it through a pipe at 80 into a convenient intermediate portion of the suction line 76, where the liquid thus injected will be 25 mixed or emulsified and the resultant mixture may be made such that pump 74 can efficiently operate on the same. Such a system is far superior to that indicated in Figures 7 and 8 in that an efficient mixing 30 action can always be obtained, but it is objectionable in the large amount of extra equipment required, amounting to an entire separate pumping system of relatively small size. After pump 74 in Figure 9 is 35 operating with a full suction line, pump 78 may be stopped or permitted to continue in operation as may be desired.

In an attempt to eliminate the additional equipment of Figure 9, and at the same 40 time, secure the same efficient mixing action, the next step is the system illustrated in Figure 10. In Figure 10, pump 78 and pipe 80 have been replaced by a separator 82 in the discharge line leading from pump 45 74 and a pipe 84 for delivering liquid from the separator and mixing it with the gas in suction line 76. When this system is started, the pump 74 will throw any liquid lying in the pump into separator 82 and 50 from there, it will flow through pipe 84 to be mixed with the gas in suction line 76. When the pump is stopped, the system will empty itself except for the lower half of the casing of pump 74 within which a small 55 quantity of water will remain, to assist in starting again. It will be seen that pump 74 now performs two functions, which functions were performed by pumps 74 and 78 in Figure 9; when the system is full, it 60 operates to deliver liquid through separator 82 to discharge pipe 90 as before, and when the system is being started, it supplies its own mixing fluid. The system indicated in Figure 10 is satisfactory for very 65 low suction lift, and can be made to oper-

ate on high lifts by the addition of a check valve 92 in the suction line below the opening of pipe 84. Such a check valve keeps the system above the same full of water when the pump is not operating. When the 70 pump is started, the gas, if any, in suction line 76 below check valve 92 will be drawn up through the check valve and mixed with sufficient liquid flowing through pipe 84 to enable the pump to handle the mixture. 75 The use of a check valve is, however, objectionable, as it is apt to leak and permit the entire system to become inoperative, as well as comprising movable parts which are 80 subject to wear.

I have discovered that it is not necessary, even for developing very high vacuums, to have the circuit or loop defined by pump 74, separator 82, pipe 84 and the upper portion of the suction line completely filled with 85 water during the priming operation. I have accordingly indicated in Figure 11 a rearrangement of parts in which the check valve 92 has been eliminated. To accomplish this, I merely form an upwardly directed U-bend 90 or goose-neck 88 in the suction line 76, and connect pipe 86, which corresponds with pipe 84 in Figure 10, to the suction line at or near the highest point of the U. In this 95 system, pipe 86 also performs a double function, as it delivers a small amount of liquid from separator 82 into the suction line for 100 mixing purposes during the priming operation, and when the pump is stopped and the system begins to empty itself, it forms an air break to prevent the contents of the 105 pump casing 74 from siphoning out of the system. A sufficient portion of the continuous loop completed by pipe 86 is thus kept 110 filled with water at all times to permit the formation of a sufficiently homogeneous emulsion or mixture during the priming operation. Upon comparison of Figure 11, 115 with Figures 1 and 3, it will be seen that the systems involved are identical.

Referring now to Figures 1 and 3, the operation is as follows:

When the pump is stopped, the liquid in discharge pipe 12 and separator 18 will flow out of the system through pipe 10, completely emptying the system, except for the liquid in the pump 14 itself and in pipes 30, 32 and pipe 16 up to the level of the opening of pipe 10 into mixing head 28. When the pump is again started, the liquid held in the pump and in pipes 30 and 32 will be started into circulation through pipe 16 and separator 18. Valve 24 is at this time left wide open, and the liquid flows from separator 18 to pipes 22 and 26 and through mixing head 28 back into the pump. In passing through mixing head 28, the liquid discharged from pipe 26 is mechanically mixed with considerable quantities of gas, 125 which is thus withdrawn from the pipe 10. 130

This mixture of gas and liquid is thrown by the pump through pipe 16 into separator 18, where the gas is separated from the liquid and passes upwardly through pipe 12 as soon as the pressure in the separator 18 has been built up to the point of opening valve 28, the liquid returning through pipes 22 and 26 to entrain further quantities of gas in head 28. Valve 28 is not essential to the 10 operation of the system, but in most installations it materially improves the functioning of the device by building up gas pressure in the separator. This pressure prevents the accumulation of liquid in the separator 15 which accumulation would in effect withdraw so much liquid from active circulation. Gas is thus continuously withdrawn from pipe 10 until the vacuum therein is sufficient to raise the liquid from the source of supply 20 to the head 28. As soon as this occurs, pump 14 begins to operate on liquid containing little or no gas and separator 18 is rapidly filled with liquid after which a supply of liquid under suitable pressure is delivered 25 from pipe 12. As soon as the priming operation is completed by the raising of liquid in pipe 10, valve 24 is completely closed. A slight opening in the valve permits air to flow from tank 18 to head 28 through valve 30 24 to prevent the contents of pump 14 and pipes 32 and 30 from siphoning over into pipe 10 when the pump is stopped. It is important that the flow through the valve be never completely stopped, and I prefer 35 to drill a small hole in the valve members employed, thus rendering complete stoppage of flow impossible.

I have found that surprisingly high suction in pipe 10 can be developed by systems 40 similar to that herein illustrated and described. The admixture of liquid and gas in head 28 may, if desired, be somewhat improved by means for throwing the liquid from pipe 26 in an irregular path, as for 45 instance, by spiral corrugations 34 on the inner surface of the pipe.

In the system illustrated in Figure 3, the actuation of valve 24 is performed manually, but I prefer to provide automatic means 50 for effecting a closure of the valve at the proper time. In Figure 1, I have illustrated a diaphragm control device 36, operative upon the occurrence of sufficient pressure in the separator 18 to move valve 24 into an 55 almost closed position. It will be obvious that as long as the priming operation continues, the gas withdrawn from pipe 10 will generate relatively low pressures in separator 18, but as soon as the separator 18 and 60 discharge pipe 12 fill with liquid, the pressure in separator 18 will operate the diaphragm device 36 and automatically close valve 24. In many instances, satisfactory 65 operation of the system is possible without 70 adjustment of valve 24 which, therefore,

merely functions to predetermine the relative effective areas of the different parts of the circuit.

The pump 14 which I employ is a centrifugal pump capable of handling a mixture of gas and liquid. Such a pump is shown in my co-pending application, Serial No. 450,349, filed March 7, 1922. It is made up as shown in Figures 4 and 5 of two parts, namely, a front plate 38, and a back 75 plate 40, in which is housed the runner 42. The casing formed of these two parts provides an outlet 44 at the upper end, surrounded by a flange 46, a portion of the flange being formed on each plate. This 80 flange is adapted to be connected to the delivery pipe for the pump.

The two parts of the casing 38 and 40 have flanges 48 and 50 for bolting together the two parts of the casing in a well known manner. The rear plate 40 provides the packing gland 52, which may be of any preferred or suitable character. At the lower portion of the plate 40, a foot member 54 is provided for mounting the pump, this foot member being in the form of a plate disposed at right angles to the main portion of the plate 40, and being connected by a reinforcing web 56 which is disposed on the back side of the back plate 40. In a similar manner, a flange 58 lies above the stuffing box 52 and connects the stuffing box with the back plate 40.

The front plate is provided with an inlet opening 60 having a bolting flange 62 about 100 the same, for attachment to the intake pipe.

Between the plates 38 and 40, I provide a cylindrical peripheral space 64 communicating with the outlet 44 through a flared discharge passage 66, which is most clearly illustrated in Figure 5. The peripheral space 64 provides a runway for the ends of the blades of the impeller 42, this impeller having, as shown in the drawings, a multiplicity of blades, the ends of which approach relatively close to the cylindrical surface of the space 64, providing only sufficient clearance to avoid rubbing against the cylindrical wall.

Between the intake opening 60 and the peripheral space 66, I provide a conical pocket or intake passageway 68, which permits the liquid to obtain a substantially radial direction before engaging the blades of the impeller 42. This conical space 68 is not occupied by any part of the impeller, hence the incoming liquid is free to distribute itself freely through this space, and to lower its speed as compared with its speed on entering the opening 60.

Without further elaboration, the foregoing will so fully explain the gist of my invention, that others may, by applying current knowledge, readily adapt the same to use under various conditions of service, with- 130

out eliminating certain features which may properly be said to constitute the essential items of novelty involved, which items are intended to be defined and secured to me by the following claims.

I claim:

1. In a self-priming pumping system, connections providing a complete circuit, means for circulating a medium through said circuit, mixing means and separating means located at spaced points in said circuit, a supply pipe associated with said mixing means and a discharge pipe associated with said separating means, and control means capable of varying the flow capacity of the portion of the circuit leading from the separating to the mixing means but incapable of completely interrupting the flow.
2. In a self-priming pumping system, a pump and connection for priming the same, said pump and connection requiring a predetermined discharge pressure for satisfactory priming, and release valve means for holding the discharge up to a pressure well above that necessary for priming.
3. In a self-priming pumping system, a pump, connections for priming the same, a discharge conduit, and pressure release means in said conduit opening at a pressure above that necessary for proper functioning of said priming means, but below the normal discharge pressure of said pump.
4. In a self-priming pumping system, a pump, connections for priming the same, a discharge conduit, pressure release means in said conduit opening at a pressure above that necessary for the proper functioning of said priming means, but below the nor-

mal discharge pressure of said pump, and control means for said priming connections for closing them at a pressure above that developed by the pump during priming and below that developed by the pump when primed.

5. In a self-priming pumping system, a pump, connections for priming the same, a discharge conduit, pressure release means in said conduit opening at a pressure above that necessary for the proper functioning of said priming means, but below the normal discharge pressure of said pump, and control means for said priming connections for closing them at a pressure above that developed by the pump during priming and below that developed by the pump when primed, said control means only partly closing said priming connections.

6. In a self-priming pumping system, a pump, inlet and discharge conduits therefor, a priming and air vent connection between said inlet and discharge conduits, part of the normal path of liquid lying below said connections, said pump developing a higher pressure when primed than during priming, control means sensitive to the pressure of discharge for preventing discharge up to a predetermined pressure, additional control means sensitive to the same pressure for constricting said connections at a predetermined pressure, both said predetermined pressures being higher than priming pressure and lower than normal discharge pressure.

In witness whereof, I hereunto subscribe my name this 28th day of April, 1921.

HARRY E. LA BOUR.
